UNITED STATES PATENT OFFICE.

HARRY T. ANDERSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

CAR FOR HOT METAL.

Application filed May 20, 1924. Serial No. 714,656.

To all whom it may concern.

Be it known that I, HARRY T. ANDERSON, a citizen of the United States, and resident of Butler, in the county of Butler and State of Pennsylvania, have invented a new and useful Improvement in Cars for Hot Metal; and I do hereby declare the following to be a full, clear, and exact description thereof.

My invention relates to railway cars, and particularly to steel cars provided with an additional or auxiliary protective side sheet.

When hot material such as iron bars, ashes and the like are placed in a car the sides of the car may become heated to such a degree that the paint or enamel will blister and peel off, thus leaving the metal exposed to the deteriorating effects of the weather and causing obliteration of car numbers, initials, etc.

One object of my invention is to provide an auxiliary construction whereby the main side sheets of a car are protected from the effects of hot lading as well as from damage by heavy materials being loaded into the car, the auxiliary structure being of such form that while it may be readily applied and removed from the car, there is little danger of it becoming accidentally displaced.

Another object rising out of the use of my invention relates to the protective means afforded by the auxiliary side sheets against damage by a magnet which may be employed to load and unload metal, such magnet tending to swing against the sides of the car during the operation of loading and unloading.

Another object of my invention is to simplify and improve generally the structure and arrangement of cars of this character.

Some of the forms which my invention may take are shown in the accompanying drawing wherein Fig. 1 is a view, partially in plan and partially in section, of an open top steel car embodying my invention; Fig. 2 is an elevational view taken on the line 2-2 of Fig. 1; Fig. 3 is an enlarged view of a portion of the apparatus of Fig. 1; Fig. 4 is a view corresponding to Fig. 3, but showing a modified form of fastening device, and Fig. 5 is a detail view of the locking plate of Fig. 4.

While I show my invention as applied to open top steel cars, it will be apparent that it is applicable to cars of other form and of material other than steel.

The car is provided with main side sheets

4 and end sheets 5 of somewhat the usual type. Stiffening angles 6 are riveted to the lower edges of the sheets 4 and the sheets are secured by means of rivets 7 to the bolster 8.

As will appear more clearly in Fig. 3, vertically extending Z bars 9 are secured to the side sheets and angles 10 are riveted to the bars. The laterally projecting flanges 9^a and 10^a of the members 9 and 10, respectively, form one portion of a sliding connection with auxiliary or inside plates 11 that are in turn provided with hook or flange portions 12 that are disposed vertically of the plates 11 and fit behind the flanges 9^a and 10^a, respectively, when the plates 11 are dropped from a point above the car to the positions shown in Figs. 1 and 2. The lower edges of plates 11 are provided with flanges 13, as shown in Fig. 2, through which bolts 13^a may pass to secure the plates 11 to the bottom sheets 14 of the car. This bolt fastening serves to prevent accidental displacement of the inside sheets 11 when the car is being dumped or when a magnet is being utilized to unload metal billets and the like therefrom. The fastening has the further advantage of being quickly releasable when it is desired to replace the sheets 11 with other sheets.

Angles 15 are secured to the bottom sheets 14 and serve as additional supports or braces for the side sheets 11. The Z-bars 9 besides supporting the plates 11 in proper position and bracing them against movement, act as stiffeners for the side sheets 4.

The end sheets 5 are provided with Z bars 9^b and angles corresponding to the members 9 and 10 that support auxiliary inside end plates 15^a in a manner similar to that in which the plates 11 are supported. The inside end plates 15^a are supported at their outer edges by angle irons 16 that are riveted to the side plates 4 and the end plates 5.

Top rails 17 are provided to protect the upper edges of the side sheets against damage, and the upper edges of plates 11 and 5 are strengthened by outwardly extending flanges as shown at 11^a in Fig. 2.

Referring to Figs. 4 and 5, I show a modified form of device for holding the inside sheets. This consists of a Z bar 19 corresponding to bar 9 of the other figures, but provided with holes through which bolts 20

may extend. The inside sheets 11^b are provided with openings 21, to receive the in-turned ends of a clamping plate 22 through which the bolts 20 extend. It will be seen that, by means of the bolts 20 and the clamping plate 22, the inside sheets 11^b are held firmly in position against the Z bar 19, and also held against vertical movement, thus making it possible to dispense with the ears 10 or hooks 12 of Fig. 3 and the bolts 13^a of Fig. 2.

The space between the sheets 4 and 11 permits of circulation of air therebetween, by reason of the space between the angles 11^a and 17 shown in Fig. 2, thus still further insuring against the side sheets 4 becoming heated. Openings may also be provided in the angles 15 at the bottom of the sheets 11, to still further facilitate circulation of air 20 between sheets 4 and 11.

It will be apparent that various changes may be made in the structure, as by substituting I beams for the bars 9 and 10, or by providing some other form of interlocking 25 connection for supporting the inside sheets 11 in operative position.

Still other changes in detail and general arrangement may be made without departing from the spirit and scope of the invention as defined in the accompanying claims.

What I claim is:

1. The combination with a car body provided with a side wall having inwardly and laterally projecting flange members secured thereto, of an inside wall having a flange member adapted to interengage with said first-named flange member.

2. The combination with an open top car provided with a side wall, of vertically disposed flanges mounted in spaced relation to said side wall, and side sheets provided with

hook portions mounted in position to interlock with said flanges.

3. The combination with an open top car provided with a side wall, of vertically disposed flanges mounted in spaced relation to said side wall, and side sheets provided with hook portions adapted to fit behind said spaced flanges when the side sheets are dropped vertically into position.

4. The combination with an open top car provided with a side wall, of vertically disposed flanges mounted in spaced relation to said side wall, side sheets provided with hook portions adapted to fit behind said spaced flanges when the side sheets are dropped vertically into position, and a detachable fastening for preventing vertical movement of said side sheets.

5. The combination with an open top car body provided with a side wall, of a vertically movable auxiliary inside wall detachably secured thereto, and means for releasably holding said auxiliary wall against vertical movement.

6. The combination with an open top car body provided with a side wall, of auxiliary inside wall sections each extending from a point adjacent to the top of the car to the floor thereof, and detachably secured thereto.

7. The combination with an open top car body provided with a side wall, of auxiliary wall sections each extending from a point adjacent to the top of the car to the floor thereof, locking means mounted in fixed relation to said side wall, and means on said auxiliary wall for effecting interlocking engagement with said locking means.

In testimony whereof I, the said HARRY T. ANDERSON, have hereunto set my hand.

HARRY T. ANDERSON.
